UNITED STATES PATENT OFFICE.

GEORGE T. JACOCKS, OF WEST HARTFORD, CONNECTICUT.

KEEL.

Application filed December 22, 1925. Serial No. 77,015.

This invention relates to improvements in keels and is particularly directed to improving and simplifying the structure of keels for small yachts, though not restricted in application to boats of any particular size.

An object of the invention is to produce a keel adapted to be fabricated of metal, die stamped, and with parts bent therefrom with small loss of metal and with extreme accuracy and positive interchangeability for quantity production of parts, whereby the keel may be assembled and whereby the ribs of the boat may be assembled upon the keel at the proper stations, aligned in a plane vertical thereto or at a predetermined angle therewith, and be secured against movement in any direction thereupon.

A further object of the invention is to produce a keel of great strength and rigidity for its weight, and adapted to have associated therewith a stem and a stern post received within the keel assembly to be held thereby against lateral displacement and riveted and braced thereto against angular displacement in a vertical mid-plane.

With these and other objects in view as may become apparent as the disclosure proceeds, the invention consists in the novel combination of elements, construction and arrangement of parts, operation and specific features to be hereinafter enlarged upon and recited in the subjoined claims, the invention being illustrated in the accompanying drawings, wherein:

Figure 1 is a side elevation of my keel structure;

Figure 2 is a rear elevation thereof;

Figure 3 is an enlarged section on line 3—3 of Fig. 1;

Figure 4 is a side elevation of a fragment of my keel;

Figure 5 is a plan of the fragment shown in Fig. 4;

Figure 6 is a section on line 6—6 of Fig. 2; and

Figure 7 is a perspective detail of a fragment of my keel, showing the application of the rib thereto, parts being modified.

Referring more particularly to the drawings the keel proper is formed of two keel plates 5 and 6 which extend as shown from end to end of the boat. A flat rolled steel bar 7 is interposed between the side plates and riveted thereto as at 8 to space the keel plates at their lower edges. A stem piece 9 of proper bow profile is stepped between the

two keel members and is riveted or otherwise secured thereto as at 10. A brace 11 may be welded or otherwise secured to the stem as at 12 and extend to enter between the keel plates where it may be riveted thereto as at 14.

A stern post 15 is similarly mounted between the keel plates and riveted therebetween as at 16 and braced therefrom as at 17. In order to provide a greater bearing surface to which may be riveted or otherwise secured the plates forming the stern, this stern post has secured to it on each side angle bars 18, secured thereto as by rivets 19, and having rivet holes 20 to which the stern plates are fastened.

The side members of the keel may be stamped from a sheet or may be built up, and in the stamping operation lugs 21 may be formed or left along the upper edge of each keel piece, and ears 22 may be turned at right angles therefrom to form a flat bearing surface for aligning the ribs in a vertical plane at a right angle to the plane of the keel and may be perforated as at 24 so that the ribs 26 of the boat structure may be secured therethrough as by rivets 25.

These ribs 26, when riveted to the ears, serve to space the side plates of the keel while the lugs of the keel hold the ribs in spaced relation thereupon.

The ears and the ribs may be cut away as at 27 so that a flat rolled steel bar 28 may be set therein, its outer surface to lie flush with the edge of the rib and ear so that the bottom plates may have a secure bearing thereupon, and this flat steel bar or keelson may be welded to the side of the keel members to strengthen the same against lateral bending.

It will be appreciated that such a structure will be less expensive to build and is designed for great strength and lightness and in such manner as to permit standardized production methods, the keel being built of three pieces and comprising but two plates and a bar riveted together and having ears integral therewith to which the ribs may be secured, eliminates the usual labor and expense in the attachment of clips riveted to the keel and to the rib at each rib station. The design permits working the keel section in a press at a great saving of labor and to absolute accuracy whereas separate clip angles cannot be made to absolutely accurate dimensions, except at much greater cost for

layout and handling. The bar is used to separate the plates at the bottom to increase the strength at the short dimension with a saving of weight.

5 While in the foregoing I have described specific embodiments and have mentioned only certain modifications, it will be appreciated that in practice I do not limit myself to such specific details as herein set forth, but may resort to any practical modifications falling within the scope of the claims:

What I claim is:

1. A keel comprising side members, a spacing strip secured to the side members at the lower edge thereof, lugs on the upper edge of the side members defining the rib stations, and ears bent from the plane of the side members on opposite sides of the keel 20 and defining the plane of the ribs.

2. A keel comprising side members, a spacing member therebetween, lugs at the rib stations integral with the side members to space the ribs along the keel, ears bent from 25 the lugs to align the ribs, and a keelson secured to the side members and associated with the ears to brace the side members against lateral bending.

3. In boat structure, a keel comprising a 30 plurality of longitudinal members; a stem, and a stern post, positioned between and embraced by the keel members; bracing between the stem and keel, and the stern post and keel, having footings between the keel members; ribs along the keel to hold the keel members in spaced relation at their upper edges; and lugs struck from the keel to position and secure the ribs in spaced relation.

4. A keel comprising a plurality of spaced

members, lugs rising from the edge of the 40 spaced members at the rib stations to position the ribs upon the spaced members, and ears bent from the plane of the spaced members into an angle with the lugs by which to align and secure the ribs. 45

5. A boat keel comprising spaced members whose upper edges define the plane from which the boat ribs spring, and eared lugs for attaching the ribs.

6. A boat keel comprising spaced side 50 members, aligned lugs on the edge of the side members defining the rib stations, and aligned ears bent from the plane of the side members at a predetermined angle thereto. 55

7. A keel comprising a plurality of spaced longitudinal members, each having lugs in lateral alignment with the lugs on an adjacent spaced member, said lugs rising from the edge of the spaced members and defining 60 the rib stations.

8. A keel comprising a plurality of longitudinal members whose upper edges define the plane from which the boat ribs spring, lugs defining the rib stations, and ears integral with the lugs and with the longitudinal members, bent from the lugs and defining the 65 plane of the ribs.

9. A keel comprising a plurality of longitudinal members whose upper edges define 70 the plane from which the boat ribs spring, with ears bent from the plane of the longitudinal members and defining with the upper edges thereof an angle such that the rib when positioned will rise in a vertical plane. 75

In testimony whereof I affix my signature.

GEORGE T. JACOCKS.
